(57) **CLAIM**

The ornamental design for a boot for an in-line skate, as shown and described.

DESCRIPTION

FIG. 1 provides a perspective view of a boot for an in-line skate showing my new design;

FIG. 2 is a side elevation view of the skate of FIG. 1, with the broken line showing a skate frame and wheels being provided for illustrative purposes only and forming no part of the claimed design;

FIG. 3 is an opposite side elevation view of the skate of FIG. 1;

FIG. 4 is a front elevation view of FIG. 1;

FIG. 5 is a rear elevation view of FIG. 1;

FIG. 6 is a top plan view of FIG. 1; and,

FIG. 7 is a bottom plan view of FIG. 1.
